Primary Examiner — Leanne Was-Englehart

(57) **CLAIM**

An ornamental design for a tracker enclosure for vehicle or container, as shown and featured in the accompanying drawings.

DESCRIPTION

FIG. 1 is a right, front perspective view of a tracker enclosure for vehicle or container in accordance with the present invention.

FIG. 2 is a top view thereof.

FIG. 3 is a bottom view thereof.

FIG. 4 is a right side elevation view thereof.

FIG. 5 is a left side view thereof.

FIG. 6 is a rear elevation view thereof; and,

FIG. 7 is a front elevation view thereof.

The broken lines in FIGS. 1-7 depict portions of the tracker enclosure for vehicle or container that form no part of the claimed design.
